UNITED STATES PATENT OFFICE.

EARL P. WEBSTER, OF NIAGARA FALLS, NEW YORK, ASSIGNOR TO THE SHREDDED WHEAT COMPANY, OF NIAGARA FALLS, NEW YORK, A CORPORATION OF NEW YORK.

CARTON FEEDING AND OPENING MEANS.

Application filed May 15, 1925. Serial No. 30,630.

This invention relates to mechanism for feeding cartons, and is adapted particularly for use with carton filling or packing devices by which articles may be introduced into the cartons in selected quantities. The mechanism of the present invention is arranged to receive cartons in folded or knock-down condition, to feed these cartons one by one, and in the feeding operation to open the cartons so as to place them in condition to be filled. The mechanism is particularly adapted for use in connection with a packing machine such as that shown in my co-pending application, Ser. No. 571,824, filed June 29, 1922, although the utility of the present invention is not limited to its use in conjunction with any particular packing machine.

In the mechanism of the present invention there is included a hopper in which a stack of cartons in knock-down condition is received. This hopper is provided with means by which the stack of cartons is advanced with a step by step movement toward the discharge end of the hopper. This end of the hopper is closed by a reciprocating plunger which is arranged to remove the end carton from the stack each time the plunger moves past the latter in one direction. This carton is advanced by the plunger into a guide-way and is held by suitable means against the face of the guide-way when the plunger retreats. During such retractile movement, a swinging element normally forming a part of one wall of the guide-way, enters the latter and contacts with the face of the carton held against the other guide-way wall. This element is provided with suction means so that when it retreats to its original position in the guide-way wall, the carton is opened up and now lies in the guide-way in front of the feeding plunger. As the latter advances to remove another knock-down carton from the stack, its forward end engages the opened carton and advances this opened carton to a position in front of other forwarding devices, which advance the carton toward its ultimate destination.

The mechanism is arranged so that cartons are fed one by one from the stack and

advanced with a step by step movement in a series to a position in front of a reciprocating plunger which delivers these open cartons to the packing station. The packing machine may be arranged to fill the cartons one at a time, or to fill several cartons simultaneously. The machine with which the present feeding mechanism is particularly adapted for use is arranged to fill two cartons simultaneously, and accordingly the cartons which are advanced from the opening and feeding devices one by one, are delivered in pairs in front of a reciprocating plunger, which advances two cartons at a time to the packing station. The cartons are fed to the packing station in a series with their ends in contact, but the arrangement of the packing devices requires that the cartons should be slightly spaced apart while being packed. Accordingly, the mechanism includes means by which a pair of cartons are fed with their ends in contact in front of the plunger, and means operating to space these cartons the required distance prior to the operation of the plunger to deliver the cartons to be packed.

For a better understanding of the invention, reference will be made to the accompanying drawings, in which:

Figure 1 is a plan view of the invention as applied, showing a portion of the packing machine, parts being broken away.

Figure 1^a is a detail section on the line 1^a—1^a, Figure 1.

Figure 2 is a plan view of the mechanism located below the main platform and in accord with the disclosure of Figure 1, parts being broken away.

Figure 3 is a section on the line 3—3, Figure 1.

Figure 4 is a perspective view of the carton hopper, the carton feed means thereof and adjacent thereto, parts being broken away.

Figure 5 is a fragmentary top plan view showing certain of the carton feed devices adjacent the packing machine proper.

Figure 6 is a similar view with parts in other positions to move the cartons into proximity to the packing machine.

Figure 7 is a view similar to Figure 6 with

the two most advanced cartons spaced apart.

Figure 8 is a similar view with the two most advanced cartons moved into register with the packing machine.

5 Figure 9 is a plan view of the mechanism at the left hand side of the machine below the main platform thereof and being a view complementary to Figure 1.

Figure 9^a is a detail section on the line 10 9^a—9^a, Figure 9.

Figure 10 is a side view of the right hand portion of the machine in accord with the showing of the plan view of Figure 1.

15 Figure 11 is a detail section on the line 11—11, Figure 1.

Figures 11^a and 11^b are detail fragmentary views of parts of the carton hopper feed means.

20 Figure 12 is a detail fragmentary front view partly in section of the carton spacing means.

Figure 12^a is a detail plan view of the same.

25 Referring now to these drawings, the mechanism is seen to include a hopper 111 which receives a stack of cartons in flattened or knock-down condition, and along which the cartons 28^a are fed intermittently step by step, each step of movement a distance 30 equal to the thickness of a flattened carton, by means of reciprocating toothed strips 360, working in guideways 361, and the teeth of which are held outwardly by springs. The springs permit the teeth to yield and the 35 strips are advanced with a step by step forward movement through a succession of steps and then restored to their original position in a single step.

40 The cartons are held against backward movement in the hopper during the return movement of the toothed strips 360 by upper and lower horizontal series of spring acting teeth 364 also held outwardly by their springs, against the tension of which the teeth are yieldable. A back plate may be placed at the rear of the charge of cartons 45 to be engaged by the teeth in the walls of the hopper, this plate preventing bulging of the cartons.

50 The strips 360 are moved in the manner described by mechanism which includes a rock shaft 366 which has an operative connection with the strips. On this rock shaft is loosely mounted a ratchet wheel 373, to 55 which is secured a cam disc 376. A rock lever 372 loosely mounted on shaft 366, carries a pawl 374 cooperating with the teeth of the ratchet wheel and a link 375 is connected at one end to the lever 372 and at the other 60 terminates in a yoke straddling a drive shaft 368. This yoke carries a roller 371 operating in a cam slot 370 in a cam disc 369 fast on drive shaft 368, and as the drive shaft rotates, the parts described cause the 65 cam 376 to advance with a step by step

movement. Mounted loosely on the shaft 368 is a rock lever 381 connected to a link 377 which terminates in a yoke 377^a straddling a bearing block for the shaft 366. A spring 385 bears at one end against this bearing block 70 and at the other enters a tubular portion of the yoke 377^a. The link 377 carries a pin 380' on which is mounted a roller 380 bearing against the surface of a cam disc 376. The opposite end of the arm 381 is connected by 75 a link 383 to the end of a lever 384 rigidly secured to the rock shaft 366.

With this arrangement, the advancing movement of the cam 376 causes the link 377 to assume different positions and the shaft 80 366 is similarly moved to different positions through the connections described. The cam 376 is so formed that the shaft 366 is moved in one direction in a series of short steps and is restored to its original position in a single 85 step. The strips 360 connected to shaft 366 have a similar step by step movement of advance and are restored to their original position in one step.

The cartons placed in the hopper in flat- 90 tened condition have their top and bottom flaps folded outwardly against the side wall and are advanced by the strips toward the discharge end of the hopper which is closed by the side of a reciprocating head 112 operating in a guide-way 113. This head is moved by a link 114 connected to a rock lever 140^a. A portion of the wall of the guide-way 113 is formed by a hollow suction head 113^a connected by a pipe 172 to a vacuum 100 chamber 171, and the wall of the guide-way 113 opposite the suction head 113^a is also hollow and connected by a pipe 172 to the vacuum chamber 171. The faces of both 105 hollow portions of the guide-way are perforated.

The wall 116, (Fig. 4) of the plunger 112 opposed to the stack of cartons is provided with a recess 117 defined at one end by a shoulder arranged to pick up a carton and move it from the end of the stack to the left (Fig. 1) in the advancing movement of the plunger. The plunger moves this carton to a position opposite the suction chamber of the guideway opposite the head 113^a, where the carton is held by suction in the retractile movement of the plunger. As the plunger returns to pick up a second carton, the head 113^a is swung inwardly to contact with the wall of the carton and as the plunger 112 again advances, the head 113^a returns to the position shown in Fig. 1 and draws the adjacent wall of the carton with it, so that the two carton walls are spaced and the latter is opened. This opening operation is completed just before the end of the plunger 112 reaches the open carton, and as the plunger advances farther it pushes the open carton ahead of it into the end of the guide-way in front of a reciprocating plunger 115 120 125 130

128. In such movement, it deposits the next folded carton in a position to be opened by the mechanism described. It will be observed that the plunger 112 moves forwardly 5 and rearwardly along the same path and in its forward movement it advances a folded carton to the opening devices and moves the previously opened carton to advancing devices.

10 The head 113^a is provided with extensions 113^b which are pivotally secured at their ends to levers similar to levers 126 (Fig. 2). The levers 126 are arranged for parallel movement and connected by a connection link 125 which is in turn connected by a link 124 to a rock lever 120. This lever is pivoted at one end to the frame, and carries a roller 121 moving in a cam slot 122 in a reciprocating slide 123. As the slide moves 20 to and fro in the operation of the machine it swings the rock lever about its pivot, causing the links 126 to move to the position indicated in dotted lines in Fig. 2. The links connected to links 126 and corresponding thereto in construction, swing to similar 25 positions about their pivot points and carry the head 113^a along an arcuate path into the guide-way in front of the plunger 112. The extent of the movement of the suction head 30 113^a is sufficient to permit the latter to engage the wall of the carton held against the stationary suction chamber in the guide-way wall, and when the head returns, the carton is opened up.

35 The open cartons advanced to the end of the guide-way by head 112, are moved forwardly through guide-way 119, by the reciprocating plunger 128. The head 128 is connected to a slide 133^a by an arm 125, this 40 slide being mounted in a suitable guide-way in the machine frame. The end of the slide is connected by a link 133 to the end of a rock lever 129 pivoted at one end to the machine frame and carrying a roller 130 operating in a cam groove 131 of a slide 132. As the slide reciprocates, the lever 129 is moved about its pivot and causes the head 45 128 to reciprocate in the guide-way 119.

At one side of the head is a barrier plate 50 5^a free to enter guide-way 113. This barrier plate is mounted for reciprocation into the guide-way and is operated by a headed pin 5^b passing through the wall of the guide-way and connected at its rear end to a link 55 5^c which is connected to plate 5^a. The rod is forced by a spring 5^d to a position in which the barrier plate enters the guide-way and the pin is in a position to be engaged by the head 128 in the return movement of 60 the latter. As a carton is being advanced by the head 112 to a position in front of the head 128, the latter forces the barrier plate out of guide-way 113. As soon as the head 112 retreats, the head 128 begins to advance 65 from a recess in the guide-way wall in which

it is received, and in such movement the barrier plate is permitted to enter the guide-way and engage the end wall of the carton in front of head 128, the plate preventing the carton from collapsing.

70 The cartons are fed along guide-way 119 with their side walls in contact, and are prevented from backing up in the guide-way by a swinging plate 128^a which slips down behind each carton as the latter is moved beyond the plate. In their movement through the guide-way 119, the cartons pass folding devices 135 which fold the bottom end flaps of the cartons inwardly, partially closing the bottom openings of the cartons. As the cartons are advanced to the forward end of the guide-way 119 they come successively in front of a plunger 137 which reciprocates at right angles to the guide-way 119 and moves the cartons into a passage 136.

75 The head 137 is carried on links 138 mounted on pins 139 at the lower ends of which are connected parallel movement levers 145, these levers being in turn connected by a suitable link connection to a 80 swinging lever 142 pivotally mounted at one end to a slide 140. The lever has an extension carrying a roller 148 which runs along the surface of a stationary cam. Spaced from the cam along one side is a guide plate 85 149 and at one end the cam has a leaf spring 149^c. In the movement of the roller along the cam, the roller forces the spring upwardly, passes beyond the end of it, and the spring then snaps down behind the roller. 90 On the return movement of the roller it rides up the spring along the opposite surface of the cam, thus giving the lever 142 a swinging movement on its pivot. In such movement it causes the head 137 to swing 95 about the pivots 139 and these pins are mounted in a moving part of the machine connected with the slide 140 so that the head swings up to operative position, as shown in Fig. 1, then advances along a 100 straight line while remaining in this position, then swings down out of the guide-way 136, and in this latter position is retracted to the end of the guide-way. During such movement another carton is advanced 105 in guide-way 119 to a position in front of head 137 and is picked up and advanced by the latter into guide-way 136 in the next cycle of movements.

110 The cartons are advanced along the guide-way 136 with their ends in contact, and are delivered to a position in front of a plunger 157 which moves the cartons to packing stations designated 28. The packing stations are separated, but the cartons are fed 115 with their ends in contact so that the two cartons to be advanced to the packing station by the head 157 must be separated in order to be moved by the head to packing position. This is accomplished by means of 120 125 130

a suction head 136^a, connected by a pipe 172 to the vacuum chamber 171. The head is connected to a slide 136^b connected by a lever 136^d to a rock arm 136^e on shaft 136^f. 5 A lever 136^h pivotally mounted at a convenient point on the machine, is connected at one end to the shaft 136^f and intermediate its ends carries a roller 136^j contacting with the surface of a cam 136^g having a projection 136^k. This cam is mounted on a shaft 179 driven at the proper speed from the main drive of the machine, and as the cam rotates, the shaft 136^f is rocked at the appropriate interval, causing a reciprocatory 10 movement of slide 136^b. As the cartons are advanced by the head 137, the first carton reaches a position in which its end is engaged by the face of the head 136^a in the reciprocation of the latter and the suction 15 of the head causes the carton to be drawn along in the return movement of the head, so that the carton is spaced from the one next to it.

The two spaced cartons are now advanced 25 to the packing stations 28 by heads 158 mounted on plunger frame 157 which is connected to a slide 155 working in guides 156 and connected by a link 154 to a rock lever 152, pivotally mounted at 153. The lever 30 152 has a roller 158^a entering a cam groove in a rotary cylinder 99, this groove encircling the cylinder and causing a swinging movement of the arm about the point 153 as a pivot as the cylinder rotates. The 35 mechanism is so arranged that when two cartons 28^a have been disposed in front of the head 158 and moved to spaced position, as shown in Fig. 7, the arm 152 is swung rearwardly by the cam groove and the head 40 158 is thus advanced to move these cartons over the packing station, as shown in Fig. 8. The head 158 is provided with carton grippers 158^b which are brought into action at the proper time to hold the cartons 45 against the side walls of the guide-way along which the cartons are advanced by head 158 to the packing station.

The slides 132, 123, and 140 are connected 50 by suitable means, and are operated by a link 140^c connected to rock lever 140^d, the latter being driven from the main drive of the machine through appropriate connections.

The vacuum in the several suction heads 55 and hollow chambers is maintained by a vacuum pump 168 having a pipe connection 169 with vacuum chamber 170, to which the various suction heads and chambers are connected by pipes 172. The pipes connected to movable chambers are of a flexible 60 construction.

The articles which are to be packed in 65 the cartons are fed by suitable means upon table 26 (Fig. 1) whence they are advanced to the cartons by the plunger head 107 car-

rying article pushers 108. The head 107 is connected to a slide 105, in turn connected by rod 104 to a lever 102 (Fig. 2) having a roller entering cam groove 159 in rotary cylinder 99. In the movement of the articles 70 to the cartons, they pass under contact pads 2^b arranged to detect the absence of an article from the group being packed and actuating appropriate mechanism to stop certain parts of the machine when an article 75 is absent.

The filled cartons are removed from filling position along guide-ways 160 by ejectors (not shown), reciprocated by an arm 164.

I claim:—

1. In a machine for packing biscuit, means for successively feeding individual flattened cartons, opening the same and feeding the opened cartons including carton feeding passages at an angle to each other and means 80 engaging the opened cartons to prevent collapse thereof during the movement of the cartons from one to the other of said passages.

2. In a machine for packing biscuit, means for successively feeding individual flattened cartons, opening the same and feeding the opened cartons including carton feeding passages at an angle to each other, and means 85 engaging the opened cartons to prevent collapse thereof during the movement from one to the other of said passages including a reciprocatory member and a spring pressed device having an operating connection with said member and adapted to be retracted against the tension of its spring in the return movement of certain of the carton feeding means.

3. In a machine for packing biscuit, means for successively feeding individual flattened cartons, opening the same, and feeding the opened cartons including a reciprocatory head adapted to feed the two most advanced cartons abreast, and means for spacing said two most advanced cartons apart prior to 100 being so fed abreast.

4. In a machine for packing biscuit, means for successively feeding individual flattened cartons, opening the same and feeding the opened cartons including a reciprocatory head adapted to feed the two most advanced 115 opened cartons abreast and having means for holding the cartons against endwise movement in one direction, and means for spacing said cartons apart prior to being so fed abreast, the carton feed means and the carton spacing means acting to hold the said two most advanced cartons against endwise movement in the opposite direction.

5. In a carton feeding and opening device, the combination of means for successively feeding flattened cartons from a supply, opening the cartons and feeding the opened cartons along a predetermined path in single file, adjacent cartons near the end 120

- of their path of travel having their opposed walls in contact, means for receiving the end pair of cartons in the file and moving them simultaneously to a selected point, and
6. In combination, a guide-way for opened cartons, means adapted to contain collapsed cartons, a reciprocating feeding member adapted to singly remove the collapsed cartons from the carton-containing means, means for opening the cartons within the 10 guide-way, means for feeding the opened cartons, means for reciprocating the feed member, and means operated therewith adapted to actuate said carton-opening means.
- 20 7. In combination, a guide-way for opened cartons, means adapted to contain collapsed cartons, a reciprocating feeding member adapted to singly remove the collapsed cartons from the carton-containing means, means for opening the cartons within the 15 guide-way, means for feeding the opened cartons, means for reciprocating the feed member, and means operated therewith adapted to actuate said carton-opening means.
- 25 8. In combination, a guide-way for opened cartons, means for feeding collapsed cartons along one wall of said guide-way, and means for opening the cartons comprising a head, pivoted means supporting the head adapted to be oscillated to swing the head diagonally across the guide-way to engage the carton to open it upon return to its normal position, a swinging 30 lever adapted to oscillate said pivoted means, and reciprocating cam means adapted to swing the lever.
- 40 9. In combination, a guide-way for opened cartons, means for feeding collapsed cartons along one wall of said guide-way, and means for opening the cartons, comprising a head, means for moving the head transversely across the guide-way to engage the carton to open it upon return to 45 its normal position, reciprocating means movable parallel to the guide-way adapted to actuate the last-named means, and means operated with the reciprocating means adapted to actuate said feeding means.
- 50 10. In combination, a guide-way for opened cartons, means for feeding collapsed cartons along one wall of said guide-way, and means for opening the cartons, comprising a head, means for moving the head transversely across the guide-way to engage the carton to open it upon return to 55 its normal position, reciprocating means movable parallel to the guide-way adapted to actuate the last-named means, means operated with the reciprocating means
- 60 adapted to actuate said feeding means, and means carried by the feeding means adapted to feed the opened cartons through the guide-way.
- 65 11. In combination, a guide-way for 70 opened cartons, comprising suction walls, and means adapted to feed the cartons through said walls into article-receiving position.
12. In combination, guide-ways for 75 opened cartons, comprising hollow suction walls perforated at their inner sides, and means for feeding opened cartons between said walls to article-receiving position.
13. In combination, a guide-way for 80 opened cartons, a second guide-way for feeding the cartons at right angles to the first guide-way, means for feeding the cartons from the first guide-way to the second guide-way and a swinging head within the 85 second guide-way adapted to swing across the end of the first guide-way to advance the cartons along the second guide-way.
14. In combination, a guide-way for 90 opened cartons, means adapted to contain collapsed cartons, a reciprocating head adapted to remove the collapsed cartons from the carton containing means, means for opening the cartons within the guide-way, means for reciprocating the feeding head, cam means movable therewith for operating said carton-opening means, a second guide-way at right angles to the first guide-way, means for feeding the cartons from the first guide-way into the second guide-way, 95 and cam means movable with said first cam means for operating said means for feeding the cartons through the second guide-way.
15. In combination, a guide-way for 100 opened cartons, means for feeding cartons therethrough, a second guide-way at right angles thereto, means for feeding cartons through said second guide-way, comprising a right-angled-shaped head, means for reciprocating the head forwardly and rearwardly to feed the cartons, and means for imparting a swinging movement to the head during its rearward reciprocation to remove it from said guide-way.
16. In combination, a guide-way for 110 opened cartons, means for feeding cartons therethrough, a second guide-way at right angles thereto, means for feeding cartons through said second guide-way, comprising a right-angle-shaped head, means for reciprocating the head forwardly and rearwardly to feed the cartons, means for imparting a swinging movement to the head during its rearward reciprocation to remove it from 115 said guide-way, and means for moving the feeding-head into feeding relation with the guide-way upon completion of its rearward movement.
17. In combination, a guide-way for 120 opened cartons, means for feeding cartons 125
- 65 130 operated with the reciprocating means

- therethrough, a second guide-way at right angles thereto, means for feeding cartons from the first guide-way through the second guide-way, comprising a reciprocating head movable across the end of the first guide-way to feed the articles therefrom to the second guide-way, and means for removing the head from the guide-way during its rearward reciprocatory movement, to permit feeding of the cartons to the end of the first guide-way.
18. In combination, a guide-way for opened cartons, means for feeding cartons therethrough, means for reciprocating said feeding means, a second guide-way at right angles to the first guide-way, means for feeding cartons therethrough, a third guide-way at right angles to the second guide-way, means for feeding cartons from said second guideway through the third guide-way, and means for operating the feed means for the second guide-way and the third guide-way cooperatively connected to the means for feeding the cartons through the first guide-way.
19. In combination, a guide-way for opened cartons, means for feeding cartons therethrough, means for reciprocating said feeding means, a second guide-way at right angles to the first guide-way, means for feeding cartons therethrough, a third guide-way at right angles to the second guide-way, means for feeding cartons from said second guide-way through the third guide-way, a cam frame movable with the means for reciprocating the feed means for the first guide-way, and a plurality of cams carried by the cam frame adapted to operate the means for feeding the cartons through the second guide-way and the third guide-way.
20. In combination, a guide-way for opened cartons, means for feeding the cartons therethrough, a guide-way at right angles thereto, means for feeding the cartons from the first guide-way through the second guide-way, comprising a reciprocating member, a feed head movably mounted for swinging movement on said reciprocating member, and means cooperating with the head during its reciprocatory movement thereto, to remove it from the guide-way during its rearward movement.
21. In combination, a guide-way for opened cartons, means for feeding the cartons therethrough, a guide-way at right angles thereto, means for feeding the cartons from the first guide-way through the second guide-way, comprising a reciprocating member, a feed head movably mounted for swinging movement on said reciprocating member, a lever carried by said reciprocating means, cam means adapted to swing the lever during the reciprocation of said means, and means connecting the lever to the movable head, whereby the head is moved out of the guide-way during its rearward reciprocation.
22. In combination, a guide-way for opened cartons, two spaced parallel guide-ways at right angles to the first guide-way, means for separating the two foremost cartons in the first guide-way to align them with the two parallel guide-ways, and means for feeding the cartons from the first guide-way into the two parallel guide-ways.
23. In combination, a guide-way for opened cartons, two spaced parallel guide-ways at right angles to the first guide-way, a reciprocating suction-head adapted to engage the foremost carton to separate it from the second carton, to align said two cartons with the two parallel guide-ways, and means for feeding the cartons from the first guide-way through the two parallel guide-ways.
24. In combination, a guide-way for opened cartons, two spaced parallel guide-ways at right angles to the first guide-way, a reciprocating hollow suction-head having perforations in its inner face, adapted to engage the foremost carton to separate it from the second carton, to align said two cartons with the two parallel guide-ways, a suction tank, a flexible connection between said tank and the head, and means for feeding the cartons from the first guide-way through the two parallel guide-ways.
25. In a machine of the character described, comprising means for successively feeding collapsed cartons, suction means for opening the cartons, feeding means adapted to move the open cartons forward, and suction means for maintaining the cartons in their opened position.
26. In a machine of the character described, comprising means for successively feeding collapsed cartons into a guide-way, suction means for opening the cartons within the guide-way, the feeding means adapted to move the opened cartons in said guide-way, and suction means for maintaining the cartons in their opened position during their movement through the guide-way.
27. In a machine of the character described, comprising means for successively feeding collapsed cartons, a swinging suction head for opening the cartons, and suction means for feeding and maintaining the cartons in their opened position.
28. In a machine of the character described, comprising a guide-way, means for successively feeding collapsed cartons to the guide-way, a swinging suction head for opening the cartons, means carried by the feeding means for moving the opened cartons in the guide-way, and suction means for holding the cartons in their opened position.
29. In a machine of the character de-

scribed, comprising a guide-way, means for successively feeding collapsed cartons to the guide-way, a swinging suction head adapted to be moved across the guide-way and en-

gage one side of the collapsed carton and move it across the guide-way, suction means for holding the opposite side of the carton against the wall of the guide-way, and means for feeding the carton along the guide-way, 10 said carton held in opened position by suction.

30. The improved method of filling cartons which comprises opening the cartons successively, successively propelling the 15 opened cartons toward filling position, the

propelled cartons advancing a row of cartons ahead of it in its movement, and maintaining open the cartons advancing toward filling position by suction.

31. The improved method of filling cartons which comprises opening the cartons successively by suction, propelling the opened cartons successively toward filling position, each carton propelled advancing a row of cartons ahead of it in its movement, and 20 maintaining open the row of cartons so advancing toward filling position by suction.

In testimony whereof I affix my signature.

EARL P. WEBSTER.
